HANDLE FOR COFFEE POTS OR THE LIKE

William Taylor Jones, Scranton, Pa., assignor to Consolidated Molded Products Corporation,
Scranton, Pa., a corporation of Delaware

Application February 19, 1949, Serial No. 969

Term of patent 14 years

(Cl. D44—29)

To all whom it may concern:

Be it known that I, William Taylor Jones, a citizen of the United States, and a resident of Scranton, county of Lackawanna, and State of Pennsylvania, have invented a new, original, and ornamental Design for a Handle for Coffee Pots or the like, of which the following is a specification, reference being had to the accompanying drawing, forming a part thereof.

I claim:

The ornamental design for a handle for coffee pots or the like, as shown.

WILLIAM TAYLOR JONES.
